WILLIAM J. OWEN, OF COLLINWOOD, OHIO, ASSIGNOR, BY DIRECT AND MESNE ASSIGNMENTS, TO PETER H. MURPHY, OF PITTSBURGH, PENNSYLVANIA.

CAR-ROOF.

1,093,201.

Specification of Letters Patent. Patented Apr. 14, 1914.

Application filed November 4, 1910. Serial No. 590,640.

To all whom it may concern:

Be it known that I, WILLIAM J. OWEN, a citizen of the United States, and a resident of Collinwood, county of Cuyahoga, 5 and State of Ohio, have invented a new and useful Improvement in Car-Roofs, of which the following is a specification, the principle of the invention being herein explained and the best mode in which I have contemplated 10 applying that principle, so as to distinguish it from other inventions.

My invention relates in general to car roofs and in particular to the construction of roofs for metal freight cars, although of 15 course, it is not limited to that one use.

The general object of the invention is the provision of a car roof which will be water tight and other advantages attained by the 20 invention will appear from the following description.

The annexed drawing and the following description set forth, in detail certain mechanism embodying the invention, such disclosed means constituting, however, but one 25 of various mechanical forms in which the principle of the invention may be used.

In said annexed drawing:—Figure 1 is a side elevation of a carline entering into my improved construction; Fig. 2 is a section 30 on the line A—A in Fig. 1; Fig. 3 is a section on the line B—B in Fig. 1; Fig. 4 is a section on the line C—C in Fig. 1; Fig. 5 is a broken section, partly in side elevation of a side of a car in which my construction 35 is used; Fig. 6 is a longitudinal section partly broken away of a car in which my construction is used, with the addition of certain parts which are not shown in the other figures and Fig. 7 is a section on the 40 line D—D in Fig. 1.

For the utilization of my improved system of roof construction, I provide a carline 1 of which a plurality will be disposed transversely along the car. The carline 1 is 45 provided in its top with a channel or depression 2 which is bounded by walls 3 and at its bottom it has outwardly projecting flanges 4. Near the respective ends of the carline its 50 depth is decreased so that vertical plates 5 are formed and outwardly beyond the plates 5 the carline is bent into the shape clearly 55 shown in Fig. 7, these outer ends being bent downwardly from a horizontal plane. At a certain point, preferably about midway be-

tween the ends of the carline, the bottom of 55 the channel 2 is bent upwardly as at 7 and this bent up portion is provided with an aperture 8.

A plurality of the carlines 1 are embodied in the car by resting upon the side plates 60 15, their outer downwardly curved ends extending over the top of the side plates 15 and sheathing 16. The purlins 14 and the ridge poles are then placed longitudinally 65 of the car and are supported on the flanges 4 of adjacent carlines. The roof members 9 are then supported on the purlins and ridge poles and have their inner edges 10 bent upwardly over the walls 3 of the channel 2 in the carline. A cap 11 is then placed 70 over the channel 2 and its walls extend downwardly outside of the bent up edges 10 of the roof members and its edges 18 are then bent parallel to the bodies of the roof members 9. The roof members 9 and the 75 cap 11 at the sides of the car are bent downwardly over the side plates 15 and sheathing 16 in conformance with the shape of the carlines 1 and bolts 17 are then used to secure the carlines, roof members and caps 80 to the sheathing and side plates.

A bracket 12 is mounted on top of the cap 11 and a running board 13 extends longitudinally of the car supported by the brackets 12. The brackets 12 and the caps 11 are provided, of course, with holes registering with the hole 8 in the carline whereby a bolt may tie the members together.

In a car constructed with a roof embodying the invention described above, it is impossible 90 for water to get in to the interior of the car. In the first place it is highly improbable that water will be forced upwardly between the cap and the roof member and into the channel of the carline, but 95 even if it does find its way to the channel it immediately runs out at the sides of the car and has no means of ingress to the interior of the car. The invention thus provides a car roof which absolutely prohibits the 100 entrance of water to the interior of the car.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In a car roof, the combination with the side plates and side sheathing, of a channel carline having side walls extending below the bottom of the channel and forming a pocket at each end into which said plates and sheathing project, the extreme ends of the carline depending below the eaves of the car, whereby the joint between the top of the side plates and sheathing and the carline is covered.

2. A carline comprising side walls, laterally extending flanges at the bottom of the side walls, the top of said side walls being rebent to form a hollow strengthening member for each of said walls, a flat spacing member between said rebent members extending in a plane below the top of the side walls from end to end of the carline except at the center of the carline where it is struck up to approximately the plane of the top of the walls to serve as a bearing for a running board saddle.

3. A carline for cars comprising side walls having laterally extending base flanges, hollow strengthening ribs integral with the top of said walls, a flat spacing member between and integral with the lower edge of said members, between the side walls, said side walls being rebent near their ends into said hollow ribs to form a pocket, the extreme ends of the carline being downwardly deflected.

4. A carline of channel shape and comprising side walls extending below the bottom of the channel and terminating in wide outwardly extending base flanges extending from end to end of the carline, said walls being reduced in height near the ends of the carline and the extreme ends of the carline being bent downwardly to form a pocket for the side plates and upper ends of the car walls, the said flanges constituting a wide flat bearing for the carline on the rear and upper faces of the side plate.

5. In a car roof, the combination with a channel carline having a pocket near each end, side plates and the upper ends of the side walls seated in said pockets, the roofing sheets having return bent vertical side flanges which extend into the channel of the carline, a cap covering the carline and vertical flanges of the roof sheets, the outer ends of the roof sheets, cap and carline being bent below the eaves of the car to constitute a hood covering the joints between the side plates, carline and side walls, and a bolt passing through the ends of the roof sheets, cap, carlines, side walls and side plate.

6. In a car roof, the combination with the side plates of metal carlines, said carlines each having a channel shape central portion and side walls projecting below said channel portion and terminating in lateral base

flanges, purlins supported by said lateral flanges, and roof covering members arranged on said purlins, said roof covering members having their side edges bent over said carline side walls and their end edges bent down over said side plates. 70

7. In a car roof, the combination with the side plates of metal carlines, said carlines each having a channel shape central portion and side walls projecting below said channel portion and terminating in lateral base flanges, purlins supported by said lateral flanges, and roof covering members arranged on said purlins, said roof covering members having their side edges bent over said carline side walls and their end edges bent down over said side plates, and a cap covering said channels and inclosing the bent edges of said roof covering members. 80

8. In a car, the combination with the side plates, of a carline provided with hollow upwardly extending spaced ridges forming a channel between them; roof members having their edges bent up over said ridges, said ridges being higher than the bodies of said members; and a cap covering said channel and having its edges bent downwardly over the bent edges of said members, said carline, roof members and cap being bent downwardly over said plates. 90

9. A carline, said carline being of greater depth between the sides of the car than beyond, and provided with upwardly extending spaced hollow ridges, forming a channel intermediate of said hollow ridges, said channel extending the whole length of the carline, part of said channel being raised between the hollow ridges and having a hole in said raised part, the bottom and sides of said channel being otherwise imperforate. 100

10. A carline, said carline being of greater depth between the sides of the car than beyond, and provided with upwardly extending spaced hollow ridges, forming a channel intermediate said hollow ridges, said channel extending the whole length of the carline, part of said channel being raised between the hollow ridges and having a hole in said raised part, the bottom and sides of said channel being otherwise imperforate 110 and said carline being bent downwardly at each end. 115

11. A carline, provided with upwardly extending hollow spaced ridges forming a channel intermediate said hollow ridges, a part of the bottom of said channel being raised and having a hole in said raised part, the bottom and sides of said channel being otherwise imperforate, and said carline being bent downwardly and overlapping the 125 car side at each end.

12. In a car, the combination of a carline provided with upwardly extending spaced ridges forming a channel between them, a part of the bottom of said channel being 130

raised intermediate of said ridges and having a hole in said raised part, the bottom and sides of said channel being otherwise imperforate; and roof members having their edges bent over said ridges.

13. In a car, the combination of a carline provided with upwardly extending spaced ridges forming a channel between them, a part of the bottom of said channel being raised by bending the metal intermediate of said ridges, the channel having a hole in said raised part, the bottom and sides of said channel being otherwise imperforate; roof members having their edges bent over said ridges; and a cap covering said channel and inclosing the bent edges of said members.

14. In a car, the combination with the side plates, of a carline provided with hollow upwardly extending spaced ridges forming a channel between them, a part of the bottom of said channel being raised intermediate of said ridges and having a hole in said raised part, the bottom and sides of said channel being otherwise imperforate; roof members having their edges bent over said ridges; and a cap covering said channel and inclosing the bent edges of said members, said carline, roof members and cap being bent downwardly over said plates.

15. In a car, the combination with the side plates; of a carline provided with upwardly extending spaced ridges forming a channel between them and with outwardly

extending flanges at its bottom; roof members having their edges bent over said ridges, said ridges being higher than the bodies of said members; a cap covering said channel and having its edges bent downwardly outside of the bent up edges of said members and then bent parallel to the bodies of said members, said carline, members and cap being bent downwardly over said plates; and means securing said carline, members and cap to said plates.

16. In a car, the combination with the side plates; of a carline provided with upwardly extending spaced ridges forming a channel between them and with outwardly extending flanges at its bottom; roof members having their edges bent over said ridges, said ridges being higher than the bodies of said members; a cap covering said channel and having its edges bent downwardly outside of the bent up edges of said members and then bent parallel to the bodies of said members, said carline, members, and cap being bent downwardly over said plates; and bolts extending through the flanges of the carline, the members, the portions of the cap parallel to the members, and said plates.

Signed by me this 1st day of November, 1910.

WILLIAM J. OWEN.
